OIL DISPENSER

Le Roy Du Bois, New York, N. Y.

Application May 4, 1946, Serial No. 667,304

5 Claims. (Cl. 222—108)

1

My invention relates to dispensers for oils or other liquids and, more particularly, to receptacles having an opening for the reception of a quantity of liquid and having another opening, preferably a nozzle, for the discharge of the liquid.

Due to the viscosity of the liquid and to other reasons, the discharge is never absolutely complete, a portion of the liquid remaining at the inner surface of the nozzle and of other parts of the receptacle. Later, this remaining liquid is apt to drip from the receptacle and to soil or spoil the place where the receptacle has been placed. Thereby, also the outer surface of the receptacle may be soiled and the receptacle can not be handled a second time without soiling the hands. An object of my invention is to avoid these drawbacks and to prevent any drippage of liquid when the receptacle is not used or has been put away.

Another object is to avoid any loss of liquid.

Further objects are to obtain these results reliably and with simple means, and to provide a structure which can be inexpensively made and easily handled.

Still other objects and advantages will appear from the following description of an exemplifying embodiment of my invention, from the appended claims and from the accompanying drawing in which:

Fig. 1 shows a cross-section of an illustrative embodiment of my invention in that position in which the dispenser is placed when not used, this cross-section being taken along the line 1—1 in Fig. 2.

Fig. 2 shows a cross-section taken along the line 2—2 in Fig. 1.

Fig. 3 shows a cross-section taken along the line 3—3 in Fig. 1.

Fig. 4 shows a side view of the same embodiment in a position in which the dispenser is used for discharging oil.

Referring to the drawing, numeral 4 indicates a housing containing a preferably cylindrical main chamber 5 and a drip chamber 6 positioned at one side of the chamber 5 and separated therefrom by a partitioning wall 7 which extends from one longitudinal side line of the housing to another. Preferably, the drip chamber 6 has a lunular cross-section adjacent to an arc of the wall of the main chamber 5 whereby the entire cross-section of the housing has a slightly elongated and well rounded shape adapted for convenient handling.

The chamber 5 has a wide opening 8 at the base of the housing 4 or at that side which is at the bottom in Figs. 1 and 2 and which is turned up

2

in the position of use shown in Fig. 4. The opposite side of the housing is closed by an end or top wall 10. The wall 7 does not reach to the end wall 10, leaving a gap near this end wall.

Another, inner end wall 9 may be arranged at a small distance from the wall 10. The wall 9 extends from the wall 7 across the main chamber 5. A space 11 is located between the end walls 9 and 10 and communicates with the drip chamber 6.

The wall 9 has an outlet or opening 12, and the wall 10 has an outlet or opening 13. The openings 12 and 13 are positioned eccentrically at the same side of the receptacle or housing as the drip chamber 6 and about at the center of the arc formed by this drip chamber. The edges of the opening 12 are preferably raised or bent in the direction to the chamber 11. A pipe 14 is affixed to the wall 10 and around the opening 13. The pipe may be suitably curved or bent and terminates in a nozzle 15.

In addition to the drip chamber 6, the housing 4 may contain an inner drip chamber 16 formed by a cylindrical partitioning wall 17 which projects from the rim of the opening 8 to the inside of the housing and terminates at some distance from the wall 9.

Preferably, the receptacle is charged with a container 18 (Fig. 4) of conventional type which contains the liquid to be dispensed. The container 18 has a cylindrical shape and is completely sealed, one flat end wall of the container being perforable or tearable. The opening 8 fits the cross-section of the container 18 or is slightly larger than the latter. Preferably, the container 18 is introduced into this opening in sealed condition, the perforable side being inserted first, and this side is opened by means provided in the interior of the chamber 5.

These means may comprise one or several knives or cutters projecting from the wall 9 to the interior of the chamber 5 in a direction to the opening 8. For example, a cutter 19 may be made of a rectangularly bent strip of sheet metal.

One arm of the strip 19 runs parallel to and is affixed to the wall 9. The other projects about parallel to the wall 7 and terminates in an edge 20 adapted to cut or break through the perforable side of the container 18. Another cutter 21 may have a part similarly affixed to the wall 9 or to the adjacent part of the strip 19, may project in an oblique direction and terminates in a cutting edge 22. Preferably, the cutter 21 projects less far than the cutter 19. A third cutter 23 may be affixed to a broad side of the cutter 21 in a posi-

tion where the broad sides of the cutters 21 and 23 are perpendicular to each other.

Rivets 24 and 25 may be used to connect the cutters with the wall 9. These rivets may pass through the walls 9 and 10 and may have necks of enlarged diameters positioned between these two walls.

The dispenser is used in a position in which the nozzle 15 points downward. The container 18 is pushed into the opening 8. Hereby, the edge 20 perforates the container 18 at a spot near the container's cylindrical wall. From then on, the projecting part of the cutter 19 acts as a guide for the further insertion of the container. During this further insertion, the cutters 21 and 23 perforate the central part of the perforable wall of the container 18, creating a wide opening therein through which the liquid can readily flow to the opening 12 and farther through the opening 13, the pipe 14 and the nozzle 15.

When the liquid has been dispensed or discharged in this manner, the emptied container 18 is removed. Then, the dispenser can be returned into the position shown in Figs. 1 and 2 and can be placed in this position without any drippage from the opening 8. Any liquid that may have remained in the pipe 14 will run along the walls of this pipe into the drip chamber 6 where it will stay until further use and reversal of the dispenser. If liquid should enter the chamber 11, for example, because the dispenser has been occasionally tilted when handled, this liquid will not pass through the opening 12, but will flow around the raised edge of this opening into the chamber 6.

If, by any chance, liquid should run from the wall 9 down the walls of the chamber 5, this liquid will be intercepted by the drip chamber 16. If the dispensed liquid is not substantially viscous or adhesive and if a considerable quantity of this liquid has remained in the pipe 14, this remained liquid may form drops which fall through the opening 13. Such drops will either fall into the drip chamber 6 or, if they pass the opening 12, into the drip chamber 16. Either the wall 7 or the wall 17 is positioned at least as far inwardly as the innermost part of the opening 13 whereby no drops falling through this opening can reach the opening 8.

If the wall 7 is positioned sufficiently inward, or if a sufficiently viscous liquid is dispensed, the chamber 16 is not absolutely necessary. So, in certain cases, the wall 17 or the chamber 16 may be omitted or may be provided merely as an additional security against drippage.

I desire it understood that my invention is not confined to the particular embodiment shown and described, the same being merely illustrative, and that my invention may be carried out in other ways without departing from the spirit of my invention as it is obvious that the particular embodiment shown and described is only one of the many that may be employed to attain the objects of my invention.

Having described the nature of my invention, what I claim and desire to protect by Letters Patent is:

1. A dispenser for liquids, comprising a housing having a base and having a top wall with an outlet; and a partitioning wall connecting two side lines of said housing and extending perpendicularly from said base toward said top wall, a gap being left between said partitioning wall and said top wall, said partitioning wall dividing said housing into a main chamber and a drip chamber and

being so positioned that said drip chamber is partially positioned vertically under said outlet, said base being closed at the bottom of said drip chamber and having an opening at the bottom of said main chamber.

2. A dispenser for liquids, comprising a housing having a base and having a top wall with an outlet; and a partitioning wall having an arc-shaped cross-section, connecting two side lines of said housing and extending perpendicularly from said base toward said top wall, a gap being left between said partitioning wall and said top wall, said partitioning wall dividing said housing into a main chamber positioned at the concave side of said partitioning wall and into a drip chamber positioned at the convex side of said partitioning wall, said partitioning wall being so positioned that said drip chamber is partially positioned vertically under said outlet, said base being closed at the bottom of said drip chamber and having an opening at the bottom of said main chamber.

3. A dispenser for liquids, comprising a housing having a base, a top wall and a tubular side wall connecting said base and said top wall, said housing having an outlet positioned eccentrically near the connecting line of said side wall and said top wall; and a partitioning wall connecting two longitudinal side lines of said side wall and extending perpendicularly from said base toward said top wall, a gap being left between said partitioning wall and said top wall, said partitioning wall having a part spaced from that longitudinal line of said side wall which is nearest to said outlet, said spaced part being positioned nearer to the central axis of said housing than the most eccentric part of said outlet, said partitioning wall dividing said housing into a drip chamber positioned between said partitioning wall and that longitudinal part of said side wall which is nearest to said outlet and into a main chamber, said base being closed at the bottom of said drip chamber and having an opening at the bottom of said main chamber.

4. A dispenser for liquids comprising a housing having a base, a top wall and a tubular side wall connecting said base and said top wall, said housing having an outlet positioned eccentrically near the connecting line of said side wall and said top wall; a partitioning wall connecting two longitudinal side lines of said side wall and extending perpendicularly from said base toward said top wall, a gap being left between said partitioning wall and said top wall, said partitioning wall having a part spaced from that longitudinal line of said side wall which is nearest to said outlet, said spaced part being positioned nearer to the central axis of said housing than the most eccentric part of said outlet, said partitioning wall dividing said housing into a drip chamber positioned between said partitioning wall and that longitudinal part of said side wall which is nearest to said outlet and into a main chamber, said base being closed at the bottom of said drip chamber and having an opening at the bottom of said main chamber; and an inner end wall positioned at a small distance from said top wall and substantially parallel thereto and extending across said main chamber, said inner end wall having an outlet opening positioned near said outlet of said housing.

5. A dispenser for liquids, comprising a housing having a base, a top wall and a tubular side wall connecting said base and said top wall, said housing having an outlet positioned eccentrically near the connecting line of said side wall and said

top wall; a partitioning wall connecting two longitudinal side lines of said side wall and extending perpendicularly from said base toward said top wall, a gap being left between said partitioning wall and said top wall, said partitioning wall dividing said housing into a main chamber and into a drip chamber positioned at the same side of said housing as said outlet; and another partitioning wall forming a cylinder extending perpendicularly from said base into said main chamber and dividing said main chamber into a second drip chamber of annular cross-section and into an inner cylindrical space, said other partitioning wall being so positioned that no part of said inner space lies vertically under 15

said outlet, said base being closed at the bottoms of said drip chambers and having an opening at the bottom of said inner space.
